US0D1026628S

(12) **United States Design Patent** (10) **Patent No.:** **US D1,026,628 S**
(45) **Date of Patent:** **** May 14, 2024**

(54) **ADHESIVE HOOK**

(71) Applicant: **Simple Living Solutions, LLC**,
Scottsdale, AZ (US)

(72) Inventor: **Jamie Limber**, Phoenix, AZ (US)

(73) Assignee: **Simple Living Solutions, LLC**,
Scottsdale, AZ (US)

(**) Term: **15 Years**

(21) Appl. No.: **29/861,476**

(22) Filed: **Nov. 30, 2022**

(51) LOC (14) Cl. **08-11**

(52) U.S. Cl.

USPC **D8/367**

(58) **Field of Classification Search**

USPC D8/367, 373; D6/323, 325, 328, 316,
D6/315

CPC F16B 45/00; H02G 3/30

(57) **CLAIM**

The ornamental design for an adhesive hook, as shown and described.

DESCRIPTION

FIG. 1 is a perspective view of an adhesive hook;
FIG. 2 is a front view of the adhesive hook;
FIG. 3 is a rear view of the adhesive hook;
FIG. 4 is a bottom view of the adhesive hook;
FIG. 5 is a top view of the adhesive hook;
FIG. 6 is a left side view of the adhesive hook;
FIG. 7 is a right side view of the adhesive hook;
FIG. 8 is a perspective view of an alternative embodiment of the adhesive hook;
FIG. 9 is a front view of the alternative embodiment of the adhesive hook;
FIG. 10 is a rear view of the alternative embodiment of the adhesive hook;
FIG. 11 is a bottom view of the alternative embodiment of the adhesive hook;
FIG. 12 is a top view of the alternative embodiment of the adhesive hook;
FIG. 13 is a left side view of the alternative embodiment of the adhesive hook; and,
FIG. 14 is a right side view of the alternative embodiment of the adhesive hook.

1 Claim, 14 Drawing Sheets
